(57) **CLAIM**

The ornamental design for a hockey helmet mask, as shown and described.

DESCRIPTION

FIG. 1 is a front perspective view of a hockey helmet mask showing my new design;
FIG. 2 is a front view thereof;
FIG. 3 is a rear view thereof;
FIG. 4 is a side view thereof;
FIG. 5 is a top view thereof;
FIG. 6 is a bottom view thereof;
FIG. 7 is a rear perspective view thereof; and,
FIG. 8 is a front perspective view thereof showing a hockey helmet with a face shield and the hockey helmet mask attached to the hockey helmet.

The broken lines in the Figures are for the purpose of illustrating portions of the hockey helmet mask that form no part of the claimed design. The dot-dash line represents the boundary of the claim thereof. The broken lines in FIG. 8 depicting a hockey helmet and face shield represent environmental subject matter that forms no part of the claimed design.

The shade lines in the Figures show contour and not surface ornamentation.
